UNITED STATES PATENT OFFICE.

VIRGIL OLDBERG, OF PEORIA, ILLINOIS, ASSIGNOR TO OLDBERG MANUFACTURING COMPANY, OF DETROIT, MICHIGAN.

MUFFLER.

1,043,966.

Specification of Letters Patent. Patented Nov. 12, 1912.

Application filed May 10, 1912. Serial No. 696,421.

To all whom it may concern:

Be it known that I, VIRGIL OLDBERG, a citizen of the United States of America, and resident of Peoria, county of Peoria, and 5 State of Illinois, have invented a certain new and useful Improvement in Mufflers, of which the following is a specification.

My invention relates to improvements in exhaust mufflers, and has for its object the 10 production of a device by means of which the noise occasioned by the discharge of waste gases from internal combustion engines is practically silenced without increasing the back pressure or reducing the power 15 of the engine.

A further object is the production of a device by means of which the exhaust when discharged is practically at the temperature of the atmosphere.

20 A further object is the production of a device by means of which the sound waves caused by the exhausting of the gas are reduced to *nil* by causing portions thereof to impinge against each other within the 25 muffler.

A further object is the production of improved means of securing the parts together in such a manner as to insure a rigid structure.

30 These and such other objects as may hereinafter appear are attained by my device, embodiments of which are illustrated in the accompanying drawings, in which—

Figure 1 represents a side elevation, 35 partly in section, of my improved muffler; Fig. 2 represents a sectional view on the line 2—2 of Fig. 1, looking in the direction indicated by the arrows; Fig. 3 represents an end view of one of the end plates; and 40 Fig. 4 represents a plan view of a portion of the central tube showing the openings. Fig. 5 represents an end view of the muffler. Fig. 6 represents a side view, partly in section, of my smaller muffler. Fig. 7 represents a sectional view on the line 7—7 of 45 Fig. 6, looking in the direction indicated by the arrows. Fig. 8 represents an end view of one of the end plates of Fig. 6. Fig. 9 represents a sectional view on the line 9—9 50 of Fig. 6, looking in the direction indicated by the arrows.

Like numerals of reference indicate like parts in the several figures of the drawing.

Referring now to the drawings—4 and 55 represent end castings or hoods formed

from any desired material, the end 4 being provided with suitable pipe connections 6 on its outer face, the exhaust pipe 7 from the engine opening through the end 5 and the short pipe 8, through which the gas is 60 discharged to the atmosphere, is screwed into the connection 6. The inner face of the casting 4 is provided with a central boss 9, 65 crew-threaded interiorly, as shown at 10, and a series of projecting rings or annuli 11 and 12, and an outer bead 13. The head 5 is provided with an outer annular flange 14 and a bead 15 corresponding with bead 13 on the opposite end, the outer casting 16 of the muffler being held in place between 70 the beads or shoulders 13—15. Fitting within the shell or casing 16, which constitutes the outer shell of the muffler, are four metal expansion tubes 17, 18, 19 and 20, together with a central tube 21 closed at its 75 lower end and screwed into the central boss 10, and forming an extension of the inlet tube 7. Fitting within the head 5 is an annular plate or ring 22 provided with a series of annular flanges or bosses 23, 24 and 25, 80 corresponding in position with the annuli 11, 12, 9 on the head 4. These rings are preferably interrupted, as clearly shown in Fig. 3. It is evident that this inner plate or ring may be dispensed with and the 85 bosses formed on the inner face of the head 5, but I prefer to use the additional plate or ring 22.

It will be noted that the annular flanges or rings 23, 24, 25, are stepped upward from 90 the outside; that is, the highest flange is the inner one, or 25. By this construction the assembling of the parts is rendered simple, the inner tube 21 being screwed into the central boss 9, and the tubes or shells 17, 18, 95 19, 20 being fitted in place and held by the annuli 11, 12, 9. The end plate 22 is placed over the ends and the end casting 5 slipped into place, after which a screw gland or threaded flanged lock nut is inserted through 100 the central opening in the end 5 and screwed onto an end of the inner tube 21, as shown at 27, the shoulder 28 of the lock nut striking against the central boss or flange 29 of the end cap 5, thus insuring a tight fit. I 105 also provide a cap screw 30 fitting about the inlet tube 7.

It is evident that the tighter the lock nut is screwed down the tighter the drums or shells will be drawn to the inlet and outlet 110

castings or ends, making a tight fitting muffler, and by holding this flange by means of the cap screw the muffler can never become loose or fall apart unless the cap screw is removed and the flanged nut unscrewed.

5 On the outer face of the end castings I provide supporting lugs 39, preferably interiorly threaded, by means of which the muffler will be supported underneath the 10 car, brackets 40 being screwed to the bottom of the car and ends 41 passing through the bottom of the bracket into and engaging the supporting lug 39.

It will be noted, by reference to the drawings, that the adjacent annuli or rings are 15 not concentric, but are alternately set off center, the purpose of which will be fully explained later. The central expansion tube 21 is provided with a longitudinal series of 20 holes 31, opening into the chamber between the outer wall of the tube 21 and the inner face of the tube 20. It will be noted that this line of openings gives access into the 25 circumferential chamber between the expansion tube 21 and the tube 20 at its narrowest point. A similar line of openings 32 is formed in the next tube 20 opening into the 30 circumferential channel between the tubes 20 and 19 at its narrowest point, which is located at an angle of 180° from the 35 opening in the former tube. The tube 19 is provided with a series of openings 33, and the tube 18 with a series of openings 34, and the tube 17 with a series of openings 35, each 40 series of openings giving access to the chamber between the tube and the next larger tube at its narrowest point. It will also be noted that air or gas passing through any 45 line of holes in any tube first strikes the inner wall of the next tube and is obliged to travel half way around the tube before finding a point of discharge. The outlet for the last passage or chamber is through the opening 36 in the head 4, and into the passage 37 leading to the discharge pipe 8.

In Figs. 6, 7, 8 and 9 I have illustrated a slightly different form of muffler and one adapted for smaller machines and one that can be more cheaply constructed. The general principle of this muffler is the same, but the number of chambers is reduced and the construction simplified accordingly. In this structure, the three shells 50, 51, 52 are supported at their lower end against flanges 55 or annuli 53, 54 on a lower end plate 55, while the upper end plate 56 is provided with a single flange or annulus 57, and is also provided with an interiorly projecting cone-shaped inlet 58, provided with a plurality of slots or openings 59 extending along the conical sides of the inlet and opening into the interior chamber 60 within the tube 52. A rod screw-threaded at its ends passes through the center of the tube 52, 60 and is secured by a nut 61 at the lower end

and by a corresponding nut 62 at the upper end within the inlet 58. A screw cap or follower gland 63 is provided, surrounding the inlet tube 64. The outlet of the gas is through the outlet tube 65 at the lower 70 end. In this particular construction the cone-shaped inlet permits a large enough area in the openings to take care of an equal or similar amount of gas entering the muffler. These openings are made to split up the 75 sound waves before the gases enter the first expansion chamber. The operation of the device in both cases is the same, it being noted that the total area of the openings in each tube, which corresponds to the smallest 80 sectional area for the flow of gas, greatly exceeds the area of the intake opening.

The outside casing of each form of my device slips over the inlet and outlet end casting, and the flanges or annuli of these 85 casting ends are slightly tapering and rounding at the top, the only purpose of the taper being to allow the pattern to be drawn from the sand without breaking or destroying the sand mold. The top of the flange is rounded 90 or made smaller to permit the outside casing to slip over it more easily. The diameter of the castings varies in size, for the reason that some molders rap their patterns harder than others, consequently the casting is 95 larger when taken from the mold, and casings or drums being cut to exact size to fit one casting would be a trifle too small to fit a casting somewhat larger. For this reason the top of the flange has been rounded 100 or made smaller, to make up for the variations in the size of the castings.

The operation of my device with respect to the muffler, as shown on Sheet 1, is as follows: The exhaust gas entering through 105 the pipe 7 into the expansion chamber 38, is partially expanded with a consequent drop in pressure. The sound waves striking the bottom of the chamber are partially reversed in direction, and upon leaving 110 through the small openings 31 are broken up into a row of small spherical wavelets which impinge upon the wall of the inner expansion tube 20 directly opposite the openings 32, at which point they re-unite and 115 form a single cylindrical disturbance or wave front on each side of the vertical openings. It will be noted that this wave front is formed in the smallest section of the chamber, which tends to materially decrease 120 its length. The gas now expands in accordance with a known and definite law, and travels in opposite directions around the outside of the tube 21, reducing the pressure of and at the same time cooling the gas. These 125 wave fronts meet on the opposite side of the tube 21 and the interference thus caused destroys their intensity and reduces the disturbance materially. The gas then passes through the openings 32 and the same result 130

happens as when the gas passes through the openings 31. This operation is repeated until the gas is finally discharged through the openings 35 into the outer channel. Each time the gas passes through the openings the volume is gradually increased, with a consequent drop in pressure and temperature, and the sound waves are further reduced in intensity.

10 It is to be noted that the gradually increasing passage between any two consecutive tubes is of specially computed dimensions, which will vary according to the service for which the muffler is to be used, and 15 with other conditions. When the gas is finally discharged through the port 36 and into the tube 8, the pressure and temperature are practically that of the atmosphere, and the sound is practically silenced.

20 It is understood that there are various details and modifications in the construction and operation of my device that may be used, without departing from the spirit of 25 my invention, which consists in utilizing the forces of the exhaust gas against itself in chambers of a predetermined dimension in order to eliminate the noise and reduce the pressure and temperature to a normal degree.

30 I claim:—

1. In a muffler, the combination with a casing, an inlet, an outlet, means within said casing for subdividing the exhaust gases, and means for causing said subdivided portions to impinge against each other, comprising a series of eccentric annular chambers of various dimensions into which said gases are successively passed.

2. In a muffler, the combination with a 40 casing, an inlet, an outlet, means within said casing for subdividing the exhaust gases, and means for causing said subdivided portions to impinge against each other, comprising a series of eccentric annular chambers of various dimensions into which said gases are successively passed, each of said 45 chambers having the smallest cross-section at the point of entry of the gas therein, and increasing in a predetermined degree up to 50 the point of discharge.

3. In a muffler, the combination with a casing, an inlet, an outlet, means within said casing for subdividing the exhaust gases, and means for causing said subdivided portions to impinge against each other, comprising a series of eccentric annular chambers of various dimensions into which said gases are successively passed, each chamber being provided with a series 55 of oppositely disposed inlets and outlets.

4. In a muffler, the combination with a 60 casing, an inlet, an outlet, means within said casing for subdividing the exhaust gases, and means for causing said subdivided portions to impinge against each other, comprising a se-

ries of eccentric annular chambers of various dimensions into which said gases are successively passed, each of said chambers having the smallest cross-section at the point of entry of the gas therein, and increasing in a 70 predetermined degree up to the point of discharge, each chamber being provided with a series of oppositely disposed inlets and outlets.

5. In a muffler, the combination with a 75 casing, an inlet, an outlet, and an expansion chamber, said expansion chamber discharging through a series of annular chambers surrounding said expansion chamber, adjacent chambers being located eccentrically with respect to each other.

6. In a muffler, the combination with a casing, an inlet, an outlet, and an expansion chamber, said expansion chamber discharging through a series of annular chambers 85 surrounding said expansion chamber, adjacent chambers being located eccentrically with respect to each other, said annular chambers being provided with oppositely disposed inlets and outlets.

7. In a muffler, the combination with a casing, an inlet, an outlet, an expansion chamber, a series of tubes of increasing diameter surrounding said chamber, each tube being provided with a series of openings, 95 the openings in adjacent tubes being substantially 180° apart, said adjacent tubes being located eccentrically with respect to the center of said casing.

8. In a muffler, the combination with a 100 casing, an inlet, an outlet, means within said casing for subdividing the exhaust gases, and means for causing said subdivided portions to impinge against each other, comprising a series of eccentric annular chambers of various dimensions into which said 105 gases are successively passed, each chamber being provided with a longitudinal series of oppositely disposed inlets and outlets.

9. In a muffler, the combination with a 110 casing, an inlet, an outlet, means within said casing for subdividing the exhaust gases, and means for causing said subdivided portions to impinge against each other, comprising a series of eccentric annular chambers of various dimensions into which said 115 gases are successively passed, each of said chambers having the smallest cross-section at the point of entry of the gas therein, and increasing in a predetermined degree up to 120 the point of discharge, each chamber being provided with a longitudinal series of oppositely disposed inlets and outlets.

10. In a muffler, the combination with a 125 casing, an inlet, an outlet, and an expansion chamber, said expansion chamber discharging through a series of annular chambers surrounding said expansion chamber, adjacent chambers being located eccentrically with respect to each other, said annular 130

chambers being provided with a series of longitudinally disposed inlets and outlets.

11. In a muffler, the combination with a casing, an inlet, an outlet, an expansion chamber, a series of tubes of increasing diameter surrounding said chamber, each tube being provided with a longitudinal series of openings, the openings in adjacent tubes being substantially 180° apart, said adjacent tubes being located eccentrically with respect to the center of said casing.

12. In a muffler, the combination with a casing, an inlet, an outlet, an expansion chamber, said expansion chamber discharging through a series of annular chambers surrounding said expansion chamber and eccentrically located with respect to each other, the ends of said casing being provided with a series of bosses against which the walls of said chambers abut.

13. In a muffler, the combination with a casing, an inlet, an outlet, and an expansion chamber, a series of tubes of increasing diameter surrounding said chamber and eccentrically located with respect to each other, each tube being provided with a series of openings arranged longitudinally of the tube, the openings in adjacent tubes being substantially 180° apart, the ends of said casing being provided with a series of bosses against which the walls of said chambers abut.

14. In a muffler, the combination with a casing, an inlet, an outlet, and an expansion chamber, a series of tubes of increasing diameter surrounding said chamber and eccentrically located with respect to each other, each tube being provided with a series of openings, the openings in adjacent tubes being substantially 180° apart, the ends of said casing being provided with a series of bosses against which the walls of said chambers abut, and means for drawing said ends together.

15. In a muffler, the combination with a

casing, an inlet, an outlet, an expansion chamber, said expansion chamber discharging through a series of annular chambers surrounding said expansion chamber and eccentrically located with respect to each other, the ends of said casing being provided with a series of bosses against which the walls of said chambers abut, the bosses on one end thereof stepping down from the center, and means for drawing said ends together.

16. In a muffler, the combination of a plurality of chambers eccentrically disposed with respect to each other as to permit a predetermined gradual increase in the volume of gas as it passes from chamber to chamber, end castings holding said chambers together, and locking means whereby said members are held rigidly together.

17. In a muffler, the combination of a plurality of chambers eccentrically disposed with respect to each other as to permit a predetermined gradual increase in the volume of gas as it passes from chamber to chamber, end castings holding said chambers together, and screw-threaded means whereby said members are held rigidly together.

18. In a muffler, the combination of a plurality of chambers eccentrically disposed with respect to each other as to permit a predetermined gradual increase in the volume of gas as it passes from chamber to chamber, end castings holding said chambers together, and locking means whereby said members are held in place, comprising a threaded flanged lock-nut adapted to engage the shell of the central chamber and fitting over an outer flange on the corresponding end casting.

Signed by me at Peoria, Peoria county, Illinois, this 29th day of April, 1912.

VIRGIL OLDBERG.
